UNITED STATES PATENT OFFICE.

HENRY J. ALTHON, OF BOSTON, MASSACHUSETTS, ASSIGNOR OF ONE-HALF TO
GEORGE W. GILL, OF MEDFORD, MASSACHUSETTS.

ANNUNCIATOR.

1,012,790.

Specification of Letters Patent. Patented Dec. 26, 1911.

Application filed July 2, 1909. Serial No. 505,583.

To all whom it may concern:

Be it known that I, HENRY J. ALTHON, a citizen of the United States, and a resident of the city of Boston, county of Suffolk, 5 State of Massachusetts, have invented certain new and useful Improvements in Announciators, of which the following is a specification.

My invention relates to mechanically operated annunciators, and especially to that 10 class of annunciators as may be used to indicate whether a person is or is not occupying a room.

In hotels, the guests or tenants are often 15 annoyed by the maid opening the door of a room or turning its knob, while the room is occupied.

It is the principal object of my invention to prevent such annoyance by announcing 20 to any one on the outside of the door the fact that the room is occupied or unoccupied.

In the accompanying drawing, I have shown an embodiment of my invention as 25 applied to a door of a room, Figure 1 being an outside or front elevation, Fig. 2 a rear elevation of the interior of the apparatus, and Fig. 3 a vertical section through said apparatus, the door and its ordinary 30 lock.

Similar characters represent like parts in all the figures.

1 is the door of a room, and 2 the ordinary lock inserted in a recess in the usual 35 manner.

3 is a plate or casing such as is usually applied to the outside of the door opposite the lock mechanism and through which passes the spindle 4 of the knob 5. The 40 plate or casing 3 is also provided with the usual keyhole 6 registering with the key-hole of the lock. Inside of the casing 3 and between it and the door 1 is a vertically 45 slidable plate 7 which is held and guided by the flanges or guides 8—8, extending inward from opposite edge walls of the casing 3. This plate or slide 7 is provided with two indicating marks 9 and 10, one above the other, and which are adapted to register with an opening 11 in the outer casing 3 when the slide 7 is at the upper and lower end respectively, of its movement. I prefer to have the indication 9 of such an appearance as to be in marked 50 contrast to that of the casing 3, and also in marked contrast to the indicator 10. For

example, the indicator 9 may be painted red and the indicator 10 may be painted white, or the indicators 9 and 10 may be marked "Out" and "In" respectively or 60 in any other manner to indicate a difference between them. The slide 7 is provided with a vertical slot 12, through which passes the knob spindle 4, said slot permitting the sliding movement of the slide 7 in spite of 65 said spindle. The slide 7 is also provided with vertical slots 13 through which the screws that secure the casing 3 to the door, pass, and said slots having a similar function to the slot 12. 70

14, 15 is a lever of the nature of a bell-crank lever, pivoted at 16, to the inside of the casing 3, and the free end of the arm 14 of said lever bearing on the lower edge of the slide 7 with said slide resting upon said 75 end of the lever. As the free end of the lever moves away from the slot 12 to the right, as shown in Fig. 2, said arm will raise the slide 7 to its uppermost position as shown in said figure. As the arm 14 moves back 80 toward the slot 12, the slide 7 will drop, still resting upon the end of the arm 14, and the parts will assume the positions shown in dotted lines in said figure. 17 is a tension spring secured to the back of the 85 slide 7 and bearing upon the arm 14 at the upper portion of its course, so as to keep the proper tension upon said arm, and prevent its falling by gravity and also prevent the falling of the slide. The lower edge of 90 the slide 7 is preferably reinforced as shown at 18, and this reinforcement is slightly notched near its outer end as at 19 to receive the toe on the free end of the arm 14 when said end has raised the slide 7 to its 95 uppermost position. This notch 19 engaging with the toe of the arm 14 is an additional means to prevent the arm 14 from falling by gravity, and secondly to prevent the slide 7 from falling until the lever 100 14, 15 is positively acted upon. The arm 14 is in the shape of a cam, or in other words, is provided with a cam surface or edge 20. The short arm of the bell-crank lever 14, 15 is in the form of a lug or ear 15. The lever 105 14, 15 is caused to be operated by a device riding over the cam edge 20 of the arm 14 to make said lever turn in one direction, and by coming in contact with the ear 15 to turn the lever in the opposite direction. 110

21 is a lever or tongue pivotally supported on a sleeve or tube 22, loosely inclosed and

bearing upon the upper round opening 23 of the keyhole 6. The tongue 21 and the sleeve 22 are slotted as shown at 24, so that in one position of the tongue they register 5 with the keyhole 6. The tongue 21 when turned in the direction of the arrow 25, rides over the cam 20 of arm 14 and turns the lever 14, 15, raising the arm 14. The turning of the tongue 21 in the direction of 10 the arrow 26 will cause said tongue to strike against the inside of the arm 15 and turn the lever 14, 15, so as to draw the arm 14 down.

Key 27, which is adapted to pass through the slots 6 and 24 and fit into the lock, is 15 provided with an ear 28 extending laterally from the shank of the key, and down into the slot 24 when it is fitted in the lock. This ear 28 preferably extends from an annular reinforced portion 29 of the key. 20 It will be seen that the key 27 is a double key, the ear 28 in the slot 24 acting to turn the tongue 21.

The operation of the above apparatus will be as follows:—The parts being in the position shown in dotted lines in Fig. 2, the door will be locked, and the indication 10 for "Out" will be seen through the opening 11 on the outside of the door, the arm 14 will be resting on the tongue 21, as shown 25 in Fig. 2, and the lower edge of the slide 7 will be resting upon the free end of the arm 14. When the tenant or holder of the room inserts his key 27 through the keyhole 6, the inner end of the key is in engagement with 30 the lock, the ear 28 will have passed through the keyhole 6 and extend down into the slot 24. When the key 27 is turned in the direction of the arrows 25 to unlock the door, the tongue 21 will ride over the cam 20 of 35 arm 14, raise said arm and correspondingly raise the slide 7, the free end of the arm 14 sliding along the reinforced portion 18 of said slide, until the toe on the free end of the arm 14 engages with the notch 19. The 40 spring 17 and the notch 19 will hold the arm 14 and the slide 7 in their uppermost position, and the indicator 9 will be in register with and displayed through the opening 11 of the casing 3, thus indicating to any one 45 outside of the door that the occupant of the room is in. A complete revolution of the tongue 21 in the direction of the arrow 25, will bring the tongue and its slot 24 to its 50 original position, and so that the key may be withdrawn. When the holder of the 55 room leaves said room, if the key is not in the lock on the outside, he should insert said key in the same manner that he did to unlock the door. Then on turning the key in 60 the direction of the arrow 26 the tongue 21 will turn until it strikes the ear 15. Any further turning of the tongue 21 in the direction of the arrow 26 will cause the arm

14 to be drawn down again to the position shown in dotted lines in Fig. 2, and the indicator 9 will then be drawn down behind the plate 3 and be covered up and the indicator 10 will be exposed through the opening 11, so as to show anyone outside of the door that the door is locked and the room is 65 unoccupied. From the above it will be seen that by the application of a laterally extending ear 28 on the shank of a key, any key that will fit the lock of the door can be 70 readily made to indicate whether the door is unlocked or locked, or whether a person is in or out of the room. It will also be 75 obvious that my invention can be readily applied to the ordinary casing or plate of a lock.

What I claim as new and desire to secure by Letters Patent of the United States is:

1. A device for use with a door, comprising a movable signal, a casing inclosing the same, and provided with opposite parallel 85 edge walls, a sliding plate supporting said signal and guided by and between said edge walls, a lever bearing on the lower edge of said plate and adapted to slide the same by riding over said edge, and also adapted to 90 retain said plate in its raised position when its bearing point with the plate is vertically over the fulcrum of the lever, a pivotal tongue adapted to engage with said lever, and said casing provided with an opening 95 adjacent to said tongue, whereby means may be inserted within said opening for directly operating said tongue, and thereby turning the lever and sliding the plate.

2. A device for use with a door, comprising 100 a movable signal, a casing inclosing the same, and provided with opposite parallel edge walls, a sliding plate supporting said signal and guided by and between said edge walls, a lever bearing on the lower edge of 105 said plate and adapted to slide the same by riding over said edge, and also adapted to retain said plate in its raised position when its bearing point with the plate is vertically over the fulcrum of the lever, and the lower 110 edge of said plate provided with a notch for engaging with said lever when in said position, a pivotal tongue adapted to engage with said lever, and said casing provided with an opening adjacent to said tongue, 115 whereby means may be inserted within said opening for directly operating said tongue, and thereby turning the lever and sliding the plate.

In testimony whereof, I have signed my 120 name to this specification, in the presence of two subscribing witnesses.

HENRY J. ALTHER.
